PNEUMATIC VALVE FOR CONTROLLING FLOW OF MATERIAL FROM A HOPPER

Eugene A. Wahl, 460 Ridgewood Ave.,
Glen Ridge, N.J. 07028

Filed Dec. 14, 1970, Ser. No. 26,443

Term of patent 14 years

Int. Cl. D15—99; D23—01

U.S. Cl. D55—1

FIG. 1 is an isometric view of a pneumatic valve for controlling flow of material from a hopper embodying my new design;

FIG. 2 is a top plan view thereof;

FIG. 3 is a bottom plan view thereof; and

FIG. 4 is another isometric view thereof showing the valve in a closed position.

I claim:

The ornamental design for pneumatic valve for controlling flow of material from a hopper, as shown.
